John B. Wickersham, of New York, N.Y.
Letters Patent No. 858. Dated Dec. 23rd 1856.

The Schedule referred to in these Letters Patent and
making part of the same.

To all to whom these presents shall come.

Be it known
that I, John B. Wickersham of the City, County and
State of New York, have invented or produced a new

and original ornamental Design for a metallic Bedstead, and I do hereby declare that the following description and annexed drawing fully illustrate the character of the same.

Fig. 1, in the drawing is an elevation of the outer side of the post at the head or foot of the bedstead. Fig. 2, is a similar view of the inner side of said post.

Fig. 3, is an edge view of said post.

Fig. 4, is a plan of the same, and

Fig. 5, is an elevation of the head or foot board in smaller size.

The design is to be cast in metal or suitable material and the top of the post is formed to resemble an acorn, beneath which leaves hanging down from the ornament above a lattice work that terminates near the horizontal rail of the bedstead as a representation of a bunch of leaves. The sides of the lattice work on the outside of the post are ornamented with semi-globular projections or knobs.

The design representing leaves, and forming the leg of the bedstead and also the junction of the leg and rail is represented in Figs 1 and 3.

The design for the bedstead head is shown in Fig. 5, and consists of ornamental wire lattice curved near the lower rail and attached to said rails forming the ornamental panel that may be used at the head of the bed or both at the head and foot of the bedstead.

I claim the ornamental design of the post leg and headboard of the bedstead as described and represented.

In witness whereof I have hereunto set my
signature this Fourth day of December 1856.
